US00D883951S

(12) **United States Design Patent** (10) **Patent No.:** **US D883,951 S**
Yan (45) **Date of Patent:** **** May 12, 2020**

(54) **WIRELESS HEADSET**

(71) Applicant: **SHENZHEN FUSHIKE ELECTRONIC CO., LTD.**, Shenzhen (CN)

(72) Inventor: **Xiaohuang Yan**, Fuzhou (CN)

(**) Term: **15 Years**

(21) Appl. No.: **29/675,043**

(22) Filed: **Dec. 28, 2018**

(51) **LOC (12) Cl.** **14-01**

(52) **U.S. Cl.**

USPC **D14/206**

(58) **Field of Classification Search**

USPC D14/206, 205, 223; D24/174; 128/864, 128/865, 866; 181/129, 130, 135; 379/430, 431; 381/380, 381, 374, 330, 381/323; 455/90.3, 575.1, 569.1

Primary Examiner — Paula Allen Greene*(74) Attorney, Agent, or Firm* — ZANIP(57) **CLAIM**

The ornamental design for a wireless headset, as shown and described.

DESCRIPTION

FIG. 1 is a perspective view of a wireless headset, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

1 Claim, 5 Drawing Sheets
